UNITED STATES PATENT OFFICE.

GEORGE HENRY GARNET, OF ALLENTOWN, PENNSYLVANIA.

DISPENSING VESSEL.

995,340.

Specification of Letters Patent. Patented June 13, 1911.

Application filed August 31, 1910. Serial No. 579,917.

To all whom it may concern:

Be it known that I, GEORGE H. GARNET, a citizen of the United States, residing at Allentown, in the county of Lehigh and 5 State of Pennsylvania, have invented certain new and useful Improvements in Dispensing Vessels; and I do hereby declare the following to be a full, clear, and exact 10 description of the invention, such as will enable others skilled in the art to which it appertains to make and use the same.

This invention relates to vessels or receptacles for dispensing liquids, and more particularly liquid soap; and it consists in 15 the novel construction and combination of the parts hereinafter fully described and claimed.

In the drawings, Figure 1 is a side view of the vessel. Fig. 2 is a plan view of the 20 vessel. Fig. 3 is a vertical section of the lower part of the vessel, showing the valves, and is drawn to a larger scale.

A is a receiver for the liquid soap. This receiver is preferably formed of glass, and 25 is substantially globular or pear-shaped in form. At its top the receiver has a flat disk B which enables it to be stood on a table in an inverted position so that it can be filled with the soap.

30 The receiver has at its lower end a neck having two screw-threaded portions C and D, a shoulder c, and a conical projection d. The projection d is arranged between the two parts C and D, and the part D is 35 smaller than the part C. The shoulder c is arranged at the bottom of the main portion of the receiver where the larger screw-threaded part C is connected to it.

E is a support for the receiver provided 40 at one end with a screw threaded socket e of thin sheet metal which engages with the screw threaded part C. The socket e has a flexible enlargement e' at its top which engages neatly with the receiver. At its other 45 end the support E has a flange or plate e' for securing it to the wash-stand.

F is a screw threaded cap of thin sheet metal which screws onto the smaller part D and which has a conical enlargement f at its 50 upper end for engaging with the conical projection d, and forming a neat joint at that point. The flexibility of the sheet metal enables the enlargement to adapt itself to the part d when the cap is screwed up.

55 G is a valve-seat which depends from the

bottom of the cap F, and g is a short tube which projects within the cap at the top of the valve-seat and which forms an annular chamber g'. The tube g is slidable within the part D, and h is a packing-washer of 60 soft compressible material inserted in the chamber g' and bearing against the bottom of the part D so that no soap can leak out.

I is a short tube the bottom edge of which forms a seat for the check-valve. This tube 65 I depends from the bottom of the main valve-seat G, and is tapered in the reverse direction from the main valve-seat.

J is the main plug-valve which is ground 70 into the valve-seat G, and j is a weight above the plug-valve for depressing it and holding it tight in its seat.

K is the check-valve which is preferably substantially globular in form. The check-valve is arranged below the tube I, and it is 75 provided with a screw threaded stem k which is screwed into a hole in the bottom of the plug-valve. This stem affords a means for adjusting the lift of the plug-valve.

The device is operated by raising the 80 valves by hand. Some of the liquid soap descends by gravity into the seat of the plug-valve, and the check-valve prevents any large quantity of soap from pouring out into the hand. When the check-valve is released 85 the weighted plug-valve descends automatically and forces out a small quantity of liquid soap into the hand. In operation the valves are tapped lightly to raise and lower them quickly, thereby letting out a suitable 90 quantity of soap.

The glass vessel enables any one to see when it requires to be refilled with soap. The larger size of the screw threaded part 95 D enables the receiver to be connected to the support after it has been refilled and the valves have been secured to it.

What I claim is:

In a dispensing device, the combination, 100 with a vessel for holding the liquid to be dispensed, said vessel having an externally screw threaded neck, of a cap provided with a screw threaded portion for engaging with the screw threads on the neck and having also a tubular projection which is slidable 105 in the neck, an annular chamber being formed between the said projection and the screw threaded portion of the cap, said cap having also a conical main valve seat depending from it and a check valve seat at 110

the bottom of the main valve seat, a main valve normally resting on the main valve seat, a check valve depending from the main valve and affording a means for raising the 5 main valve, and packing material arranged in the said annular chamber between the cap and the end of the said neck.

In testimony whereof I have affixed my signature in the presence of two witnesses.

GEORGE HENRY GARNET.
